UNITED STATES PATENT OFFICE.

WILLIAM H. BALDWIN AND CHARLES T. PLUMMER, OF DULUTH, MINNESOTA.

DRUM.

1,420,233.

Specification of Letters Patent. Patented June 20, 1922.

Application filed February 7, 1922. Serial No. 534,767.

To all whom it may concern:

Be it known that we, WILLIAM H. BALDWIN and CHARLES T. PLUMMER, citizens of the United States of America, and residents, respectively, of Duluth, St. Louis County, Minnesota, have invented certain new and useful Improvements in Drums, of which the following is a full and clear specification.

10 Drummers are now accustomed to use a small drum for orchestra work and a deeper drum for band work, necessitating their having two or more drums if they are engaged in both lines of employment. It is 15 the object of our invention to provide a drum which, by a telescopic action, can be made small to bring the heads closer together for orchestra work or enlarged to increase the distance between the heads for 20 band work, the construction being such that the parts may be clamped together by means accessible from the exterior of the drum body at any point within the range of their adjustable capacity. It will be 25 understood that this invention is applicable to bass drums as well as the smaller types of drums.

In the drawing—

Fig. 1 is a perspective view;

30 Fig. 2 is a vertical sectional view of a portion of the drum;

Figs. 3 and 4 are views of details herein-after described.

Referring to the drawing annexed by 35 reference-characters, 5 designates two end-sections of the cylindrical body and 6 the intermediate or central section of the body, this latter being slidable into the adjacent ends of the main sections 5 and being fitted 40 nicely against the interior faces thereof. The end-sections 5 are provided with the usual heads 7, and suitable devices are pro- 45 vided for clamping the central section to the end or main sections in their adjusted posi-

tions.

The clamping devices we prefer using consist of two series of set-screws 8 arranged at spaced intervals around the drum, one series being carried by each of the main 50 sections 5, the clamp-screws being located at the inner ends of said main sections 5. The inner threaded ends of these clamp-screws extend through longitudinal slots 9 formed in the central section and are 55 tapped through clamp-plates 10 which, when the clamp-screws are tightened, are

drawn hard against the inner face of the central section 6, to thereby clamp the parts in their adjusted positions. These clamp-plates 10 are guided between longitudinal 60 flanges or ways 11 fastened to the interior of the face of the central section 6, these flanges 11 serving not only to guide the central section 6 in its movements upon the main sections 5, but also serving to prevent 65 rotation of the clamp-plates 10, thereby enabling said plates 10 to serve as nuts for the clamp-screws. These clamp-plates 10 are long enough to close the portions of the slots 9 which extend beyond the inner edges 70 of the main sections 5 and thus confine the air in the drum. As shown in Fig. 3, these clamp-plates 10 are dovetailed between the ways 11 to thereby prevent undue inward movement of the clamp-plates 10 when the 75 clamp-screws are loosened.

It will be observed that for a small drum the parts may be telescoped sufficiently to bring the inner edges of the main-sections 5 close together or in contact, and that for 80 a larger drum the sections may be slid apart to the limit of the slots 9. When the parts are thus adjusted to obtain the proper distances between the heads 7, they may be, by the devices illustrated, clamped as rigidly 85 together against loosening or vibration as is the usual non-adjustable drum. The beads 6' fastened to the edges of the central section serve to reinforce the section.

We do not desire to be understood as limit- 90 ing ourselves to the precise details of construction and arrangement shown, as variations and modifications therefrom may be made without departing from the spirit and scope of our invention and improvements. 95 We therefore reserve the right to all such variations and modifications as properly fall within the scope of our invention and improvements as set forth in the terms of the following claims.

100 What we claim is:

1. A drum comprising a body made of two outer sections and a central section telescoped within said outer sections, and means accessible from the exterior for clamping 105 the sections in their adjusted positions, whereby a single drum may be converted from a large drum to a small drum and vice versa.

2. A drum comprising a body made of 110 telescopic sections to thereby permit the distance between the heads to be varied, and

means accessible from the exterior for clamping the parts in each of their adjusted positions to thereby enable the drum to be converted from a small drum to a large 5 drum and vice versa.

3. A drum comprising a body made of telescoping sections to thereby vary the distance between the heads, said body embodying a central section telescoping inside of 10 the adjacent sections, said central section being provided with longitudinal slots at intervals, clamp-screws carried by the main sections and extending inwardly through said slots, and plates on the inner ends of 15 said clamp-screws adapted to clamp against the inner face of the central section.

4. A drum comprising a body made of telescoping sections to thereby vary the distance between the heads, said body embodying a central section telescoping inside of 20 the adjacent sections, said central section being provided with longitudinal slots at intervals, clamp-screws carried by the main sections and extending inwardly through 25 said slots, and plates on the inner ends of said clamp-screws adapted to clamp against

the inner face of the central section, said plates being long enough to close the ends of the slots which project beyond the main sections.

5. A drum comprising a body made of 30 telescoping sections to thereby vary the distance between the heads, said body embodying a central section telescoping inside of the adjacent sections, said central section being provided with longitudinal slots at intervals, 35 clamp-screws carried by the main sections and extending inwardly through said slots, and plates on the inner ends of said clamp-screws adapted to clamp against the inner face of the central section, said plates 40 being long enough to close the ends of the slots which project beyond the main sections, means being provided on the interior of the central section for guiding said central section in its telescopic movements. 45

In testimony whereof we hereunto affix our signatures this 4th day of February 1922.

WILLIAM H. BALDWIN.
CHARLES T. PLUMMER.
